UNITED STATES PATENT OFFICE.

GEORGE J. JONES AND EDWIN J. BLANNING, OF NEW CASTLE, PENNSYLVANIA.

FRICTION WRENCH.

Application filed October 7, 1924. Serial No. 742,194.

To all whom it may concern:

Be it known that we, GEORGE J. JONES and EDWIN J. BLANNING, citizens of the United States of America, residing at New Castle, in the county of Lawrence and State of Pennsylvania, have invented new and useful Improvements in Friction Wrenches, of which the following is a specification.

The object of the invention is to provide a device of the kind indicated in which the nut-engaging head is frictionally engaged by the holder during the turning of the head in operation, as in unscrewing or screwing up a nut, or rotating a shaft or spindle, thus accomplishing all the advantages of the conventional ratchet wrench without the disadvantages inherent in the latter, such as the pawls breaking or failing to take hold.

With this object in view, the invention consists in the construction and combination of parts of which a preferred embodiment is illustrated in the accompanying drawings, wherein:

Figure 1 is a plan view of the invention, Fig. 2 is an edge view, and

Fig. 3 is a transverse sectional view on the plane indicated by the line 3—3 of Fig. 1.

The nut-engaging head 1, which is circular, is provided with a peripheral V-shaped rib 2 from which the corner edge is removed to leave a flat surface 3. The head is provided with a polygonal opening 4 constituting a nut seat and the head is adapted to be carried by and operated by a holder having jaw members 5 and 6 pivotally connected, as by a hinge pin 7, the jaw members interiorly being grooved for the reception of the peripheral rib 2, the groove cross sectionally corresponding to the cross-sectional contour of the rib with the exception that the converging side of the groove merges into a common line to leave a clearance space between the flat 3 and the extreme bottom of the groove.

The jaws 5 and 6 are semi-circular in plan and to the latter there is pivotally connected the lever 8 as by a hinge pin 9 and this lever has connected with its shank 10 the handle 11. The jaw 5 is provided with a radial

arm 12 to which are connected, by means of the pivot pins 14, the links 15, the latter being disposed on opposite sides of the arm 12 so as to engage the lever 8 on opposite sides with which they are connected by means of a pin 16.

Obviously, pivotal movement of the lever 8 on the pin 9 in one direction will tend to separate the jaws 5 and 6, thus precluding frictional gripping action on the nut head, whereas movement in the other direction will tend to bring the jaws together into firm gripping engagement with the nut head. Thus, oscillation of the device will first effect gripping action on the nut head, then release it from the nut head and then again grip it and so on, so that an intermittent rotary movement in one direction is communicated to the nut head by the oscillation of the handle 11 and the nut may be screwed off or screwed on, depending on the manner in which the device is attached.

The rib 2 being V-shaped in cross-section and engaging corresponding grooves in the jaws, it may be inverted should certain conditions require a nut head having its opposite faces formed differently. However, in the present disclosure, no inversion of the nut head is necessary. The device as a whole may be inverted when it is desired to screw a nut up, if the previous disposition of the device is such as to effect an unscrewing operation.

The invention having been described, what is claimed as new and useful is:

A friction wrench comprising a nut or bolt turning head, hingedly connected jaws disposed in surrounding relation to said head, and a manual oscillatory element having a pivotal connection with one jaw and a link connection with the other jaw, the head being provided with a peripheral rib transversely triangular, and the jaws being formed with a correspondingly shaped groove for the reception of said rib.

In testimony whereof we affix our signatures.

GEORGE J. JONES.
EDWIN J. BLANNING.
